SPARK PLUG TESTER

Kenneth W. Huntwork, Rte. 5, Gladwin, Mich. 48624

Filed Apr. 27, 1970, Ser. No. 22,670

Term of patent 14 years

Int. Cl. D10—10

U.S. Cl. D26—1

FIG. 1

FIG. 2

FIG. 3

FIG. 4

FIG. 6

FIG. 5

FIG. 1 is a front elevational view of a spark plug tester showing my new design;

FIG. 2 is a side elevational view of the design, it being understood that the opposite side is a mirror image thereof;

FIG. 3 is a rear elevational view of the design;

FIG. 4 is a bottom plan view thereof;

FIG. 5 is a perspective view of the design; and

FIG. 6 is a top plan view of the design.

I claim:

The ornamental design for a spark plug tester, as shown and described.
